UNITED STATES PATENT OFFICE

152,346

DESIGN FOR A RECLINING CHAIR OR SIMILAR ARTICLE

Eugene J. Lux, New York, N. Y., assignor to Columbia Protekosit Company, Inc., Carlstadt, N. J., a corporation of New Jersey

Application March 28, 1947, Serial No. 138,021

Term of patent 7 years

(Cl. D15—11)

To all whom it may concern:

Be it known that I, Eugene J. Lux, a citizen of the United States, and resident of New York city, in the county of New York and State of New York, have invented a new, original, and ornamental Design for a Reclining Chair or Similar Article, of which the following is a specification, reference being had to the accompanying drawing, forming a part thereof, and of which Fig. 1 is a view in side elevation of a reclining chair or similar article showing my new design; Fig. 2 is a vertical sectional view taken on the line 2—2 of Fig. 3; Fig. 3 is a top plan view; Fig. 4 is a view in rear end elevation; Fig. 5 is a fragmentary sectional view taken on the line 5—5 of Fig. 1; and Fig. 6 is a side perspective view.

I claim:

The ornamental design for a reclining chair or similar article substantially as shown and described.

EUGENE J. LUX.
